(57) CLAIM

The ornamental design for a trivet, as shown and described.

DESCRIPTION

FIG. 1 is a perspective view of a trivet showing our new design.

FIG. 2 is a front view thereof, a rear view being the same as the front view.

FIG. 3 is a right side view thereof, a left side view being the same as the right side view.

FIG. 4 is a top view thereof; and,

FIG. 5 is a bottom view thereof.

The broken lines in the drawing depict portions of the trivet that form no part of the claimed design.
